UNITED STATES PATENT OFFICE.

LAWRENCE R. BABCOCK, OF KELLY, NEW MEXICO.

RAILROAD TIE.

Application filed August 12, 1922. Serial No. 581,513.

To all whom it may concern:

Be it known that I, LAWRENCE ROLLAND BABCOCK, a citizen of the United States, residing at Kelly, in the county of Socorro and State of New Mexico, have invented certain new and useful Improvements in Railroad Ties, of which the following is a specification, reference being had to the accompanying drawings.

10 This invention relates to railway ties, and has for its object to provide a tie capable of being formed from a composition or imitation stone and provided with means for firmly securing the rails to the tie.

15 It is another object of the invention to provide a railway tie composed of a composition and provided with substantial rail supporting means, said supporting means including means for holding a rail thereto, and means for the reception of the conventional form of rail spike.

20 It is a further object of the invention to provide a rail tie of this character including a metallic rail supporting member provided 25 with means adapted to receive and frictionally engage a conventional form of rail spike to hold said rail spike in engagement with the rail, similar to the wooden tie without requiring the use of wood or like perishable material.

25 With these and other objects in view, the invention consists in the improved construction and arrangement of parts to be herein-after more particularly described, fully 30 claimed and illustrated in the accompanying drawings, in which:

35 Figure 1 is a longitudinal sectional view of a railway tie constructed in accordance with an embodiment of the invention;

40 Figure 2 is a sectional view of one of the rail supporting means and the spike holding means; and

45 Figure 3 is a top plan view of one of the supporting means, the spikes being shown in section, the rail indicated by dotted lines.

50 Referring to the drawings, 5 designates a railroad tie of standard size composed of concrete or like composition, each end portion of the tie being provided with rail supporting members 6 and 7, preferably constructed of metal. Each rail supporting member comprises a base plate 8 relatively thick, said plate being adapted to rest upon the top of the tie and is provided with a 55 relatively large opening 9 and a small opening 10. Depending from the lower face of

the plate and formed integral with the plate are side members 11 and 12, the lower edges of said side members being concave for the admission of concrete when the tie is formed. 60

Depending from and formed integral with the lower face of the base plate 8 and inwardly of the ends of the base plate are end members 13 and 14, each of said end members having a foot 15 and reinforcing ribs 65 16, the feet 15 extending outwardly of the end members. By this means a compartment 17 is formed for the reception of concrete. Portions of said concrete may be passed through the opening 9. Through the cooperation of the projecting ends of the plate 8 and the feet 15, additional compartments are formed for the reception of concrete, so that there is no possibility of the supporting means being disengaged from the tie. 70

75 Disposed inwardly of the end member 14 and adjacent said end member is a wall 18, said wall cooperating with the end portions of the side members and end member 14 to provide a socket or compartment 19. The 80 end portions of the longitudinal walls formed by the end members 14 and wall 18 are provided with recesses 20, while extending centrally of the inner face of the wall 18 and end member 14 are spacing ribs 21. These 85 ribs are disposed in alignment and centrally of the socket. The socket 19 is intended to

90 receive a pair of resilient plates 22, each plate being relatively long and corresponding in width to the depth of the socket. The 95 end portions 23 and 23^a of each of the resilient plates are extended at right angles to the body portion of the plate and in parallel relation to each other, the distance between the outer face of the angularly disposed ends being slightly greater than the length of the socket. The end portions 23 and 23^a are arranged so that the extremities of said 100

end portions extend into the recesses 20 in the socket. This positions the major portion of each plate in confronting relation to the other. Each spacing rib 21 is intended to engage the central portion of one of the plates, so as to provide a relatively small space between the plates. This space is considerably smaller than the thickness of a rail spike. The recesses 20 of the socket also extend through the edges of the openings of the base plate 8. The lower ends of the recesses 20 are closed by stops 24^a. 110

Carried by the upper surface of the base plate 8, adjacent the end member 13 is a rail

clamp 25, said rail clamp having the usual undercut beveled face 26 adapted to engage the base of the rail. The clamp 25, however, is stationary.

5 In the formation of the tie, that is, before the composition has been deposited in the mold of the tie, a pair of tie rods 27 are extended longitudinally of the tie, the ends of each rod being extended in angular relation 10 to the major portion of the rod and through openings 28 provided in the feet 15 of the end members 14 of each supporting member. Nuts 29 are threaded on the ends of the tie rods to hold them in engagement with the 15 supporting members. It is of course obvious that the tie rods are embedded in the tie, and in addition to the resistance offered by the concrete, serve to prevent spreading of the rails by preventing movement of the supporting members toward the ends of the tie. 20

When the tie is constructed, the supporting members are placed so that the clamps 25 thereof are disposed one adjacent the end of the tie and the other inwardly of other 25 end of the tie. In other words, both of the clamps 25 extend in the same direction. The purpose of this is to permit the rails to be firmly braced and guarded against spreading, it being the intention to place one tie 30 with the clamps 25 facing in one direction and the adjacent tie with the clamps 25 facing in the opposite direction so that each tie alternates, thus providing a rigid structure for firmly holding the rails. The jaw 35 of each clamp is intended to engage the base of the rail A in the usual manner. This positions the opposite side of the base of the rail closely adjacent the socket member and the resilient plates 22. The spaces on 40 each side of the guide ribs 21 and between the resilient plates are intended to receive a conventional form of railroad spike B. In view of the fact that the space between the plates is considerably smaller than the spike, 45 and the plates though resilient are not flexible, the spike B may be driven home the same as if the spike was inserted in a wooden tie.

The confronting faces frictionally engage 50 the spike and hold it more securely than it would be held in a wooden tie. The spacing ribs 21 protect the plates from being moved away from each other at their central portion and through the cooperation of the 55 ends of the plates which are disposed in the recesses 20, two sockets are substantially formed for the spikes, each plate firmly engaging one side of each spike so that change of temperature or vibration of the train will

not cause movement of the spike. In addition to this, the side thrust of the train which is toward the ends of the tie is directed against the clamp 25, the strain from the clamp being indirectly transmitted to the tie rod and the tie. 60 65

From the foregoing it will be readily seen that this invention provides a novel form of railway tie capable of being formed from any composition used in the formation of imitation stone. The tie is also provided 70 with metallic rail supporting means capable of using the conventional form of rail spikes. In addition to this, the tie includes means for preventing spreading of the rails without causing the strain to be applied to the 75 conventional form of spikes used as part of the fastening means for the rails, and wherein the fastening means are not affected by the disintegrating forces which render the 80 present type of rail fastening means inefficient.

What is claimed is:—

1. A railway tie embodying a composition body, a metallic rail supporting member embedded in each end portion of the tie, each rail supporting member consisting of a metallic shell adapted to receive a portion of the composition, a rail clamp carried by one end portion of the shell, the other end portion of the shell being provided with a 85 socket, resilient plates extending longitudinally of the socket in spaced relation to each other and the adjacent walls of the socket, and rail spikes clamped between said plates within the socket. 90 95

2. A railway tie comprising a composition tie or body member, a metallic supporting shell embedded in each end portion of the tie, said shell including a base plate, walls depending from the lower surface and inwardly of the edges of the plate, certain of said walls having anchoring feet, one end portion of the shell having a rail clamp, the opposite end portion having a compartment formed therein, spacing ribs projecting from the longitudinal walls of the compartment and centrally of the compartment, recesses formed in the corners of the compartment, and a pair of resilient plates having angular ends, said plates being disposed in the socket in confronting relation, the ends of said plates being disposed in the recesses, and rail spikes driven between said plates on each side of the guide ribs for securing the rails to the shell. 100 105 110 115

In testimony whereof I hereunto affix my signature.

LAWRENCE R. BABCOCK.
